FOLDING TABLE

Udo K. Johannsen, Cortland, N. Y., assignor to
 The Brewer-Titchener Corporation, Cortland,
 N. Y., a corporation of New York

Application July 17, 1936, Serial No. 91,023

4 Claims. (Cl. 38—119)

My invention broadly relates to portable folding tables of the fully automatic type and is more particularly concerned with a collapsible ironing board stand comprising a three legged chassis 5 in which the legs are adapted to compactly fold flatwise underneath one face of such board and to be manipulated in a simple manner.

A pair of complementary or so-called rear legs have one end thereof directly pivoted to the top board and a single inclined or so-called front leg may be similarly attached in substantial alignment with the axis of the rear leg pivots. All my rigid legs are positively actuated in unison between their respective erected and collapsible 15 positions by the use of a novel actuating gear. Such controlled movement is herein brought about by a manipulative primary toggle linkage of which one free link end is pivoted to the rear leg structure intermediate the ends thereof and 20 the other free end of which linkage is pivoted underneath the board. The inclined front leg is in turn pivotally hooked up by an auxiliary toggle linkage that extends between said rear leg structure and the floor contacting end of the 25 front leg.

Stop means prevent said auxiliary linkage from reaching full toggle alignment in both the collapsed and erected table positions. By this means, the primary linkage may be freely manipulated through a wide angular range without being stalled by its cooperating linkage.

In addition, my pair of rear legs are equipped with pivotally offset brace straps which bring about a lateral spread on part of the floor contacting leg ends simultaneous with the unfolding thereof. The actuating gear herein resorted to is especially suited for an understructure comprising wooden slats that may be operatively interconnected by simple hardware. Each such 35 rigid table leg combines ample stiffness with low chassis weight that shall not prove burdensome to women when carried to or from a storage closet.

The object of the present invention is to provide for a sturdy folding table of the character indicated and one possessing comparatively few essential pivotal points that are not likely to become rickety from wear after extended use or allow the superstructure to sway abnormally under 45 its anticipated loading. My table improvements are further designed for rapid fabrication on an extensive scale at a low productive cost.

Reference is had to the one sheet of drawings which are illustrative of a preferred exemplification and in which drawing:

Fig. 1 represents an elevational side view of an erected ironing board assembly equipped with my devices, and Fig. 2 is a rear end view thereof.

Figs. 3 and 4 respectively, show a side and a bottom view of my chassis when fully collapsed. 5

Figs. 5 and 6 are fragmental details respectively taken along lines 5—5 and 6—6 of Fig. 1.

Referring more specifically to the drawing, the numerals 10 and 11 respectively designate a pair of laterally spaced rear legs. The upper end of 10 each such leg is pivoted at 12 to one board face 13. An intermediate pivot 14 is also located between the respective ends of each rear leg.

This rear leg structure is preferably of a type in which the floor contacting ends are widely 15 spread apart into the Fig. 2 position when the chassis is unfolded. To this end, I may resort to complementary brace straps such as 15 of which one end is pivoted to a rear leg while each opposite strap end is pivotally attached by a metal 20 bracket to said one board face at 16 but in an axially offset relation to the corresponding rear leg pivot 12. When collapsed, the rear legs will then fall within the board width confines in the Fig. 4 manner. 25

My primary or rear leg toggle linkage is of the jack-knife type and may comprise a pair of strut-like links such as 17 having one of their respective free ends attached to an associated intermediate pivot 14, as shown. The opposite link ends 30 are pivotally adjoined at 18 to a common guide link 19, preferably made out of a strip of wood and the free end of which guide link is pivoted to the board face at 20. The pivot 18 is purposefully disposed between the ends of such adjoined 35 toggle links to provide for a strutlike link extension 21 arranged to thrust as a prop agency against the board face in erected leg position. The guide link extension 22 is thereby kept spaced outwardly away from said face and its 40 terminal preferably provided with a cleared loop or finger piece 23 by which to swing the link 19 through a wide angle of approximately 180° into its folded position 18'. If preferred, the spaced link extension 22 may as a handle, be directly 45 grasped to perform a like function.

The inclined front leg 24 may be pivotally attached to the board coincident with the rear leg pivot 12. As depicted in Figs. 2 and 4, said wooden front leg may be bifurcated by the use of 50 companion slats of which the branched ends respectively lead to one of the complementary pivots 12 (see Fig. 4). A foot pivot 25 is located closely adjacent to the converging lower or floor contacting end of the leg 24. An auxiliary toggle 55

linkage of the collapsible type interconnects said pivot 25 with the intermediate pivot 14 and as such, may comprise a pair of relatively short link components 26 and corresponding relatively long or tension rod components 27 that are jointed at 28, preferably by the use of a loose slot connection.

As indicated in Fig. 1 by a dotted and dashed reference line A, the components of said auxiliary linkage when extended, are prevented from reaching their respective aligned dead center positions by the use of a common stop lug 29. Such lug preferably spans the links 26 and is made to abut the front leg. The linkage thereby obviates a stalling of the primary linkage when the erected table legs are to be collapsed and said stop lug precludes such buckled toggle dropping through the alignment position A even should the erected table legs be turned upside down during the folding thereof.

As a further feature, it is preferred to form my complementary tension links 27 out of a one-piece metal rod that is given a bail shape (see Figs. 4 and 5) of which the intermediate nose portion 28 is threaded through the link slots while the bail terminals are each outturned into headed trunnions (see Fig. 6) that respectively constitute the intermediate pivots 14. The end of the wooden link 17 may be metal sheathed by an apertured cap 30 to reduce trunnion wear.

The mode of folding my table legs is indicated by dotted lines in Fig. 1. In erected table position, the guide link 19 is directed rearwardly toward the pivot 12 and this brings the link extension 21 into abutment with the board face 13. The primary linkage then stands buckled through its dead center position and by virtue of the fixed bracket pivot 20, the rear legs 10 and 11 will be rigidly held against collapse. The extended auxiliary toggle becomes tensioned when the ironing board is loaded downwardly but the linkage components are not allowed to assume extended alignment because of the stop lug 29. The weight of the toggle links 26 and 27 are kept relatively light so as not to draw the front and rear legs together. When erected, the board is kept exceptionally rigid under load, partly because the foot pivot 25 is located near the floor contacting end of the inclined leg 24 rather than in the mid region thereof where a certain amount of lateral flexure would be expected.

A grasping of the finger piece 23 allows the link 19 to be swung into its dotted depending position of Fig. 1 when the auxiliary linkage will partially collapse as shown in dotted outline and thereby carry the front leg toward the board in unison with a similar rear leg movement. When the primary toggle joint 18 reaches its outermost position 18', the understructure assumes the folded Fig. 4 position. In that relationship, the stop lug 29 abuts a portion of the front leg 24 and again prevents the secondary toggle from reaching its inverted dead center position; hence, the linked understructure is kept free to unfold by a reversal of the described guide link movements without any interlocking effects.

A noteworthy attribute of the present table structure lies in its relatively simple linkage adapted to automatically unfold from a centralized manipulative point such as the link 19, and still bring about a spreading of the rear legs. In erected position, the several legs are automatically retained without need of any supplementary latch device. In addition, the auxiliary col-

lapsible toggle linkage is not dependent upon the use of a loose ended tension rod of the conventional slip type likely to become entangled when a collapsed table is carried about. When folded, the board may be conveniently hung up by the 5 forwardly overhanging loop 23.

Other advantages inherent in my table chassis are believed apparent to those skilled in this art, it being obvious that the same underlying structural principles may be used in associations other 10 than for ironing boards, and that various modifications in design may readily be resorted to in likewise carrying out the illustrative embodiment, all without departing from the spirit and scope of my invention, heretofore described and more 15 particularly pointed out in the appended claims.

I claim:

1. In a collapsible table or the like adapted to unfold into erected position, a top board, a front leg having one end region pivoted to one board 20 face, a foot pivot carried by the opposite end region of the front leg, a rear leg structure also pivoted to the board face, supplementary pivot means located on said structure between the ends thereof, a primary toggle linkage including a 25 strutlike link which intermediate its ends is pivotally jointed to one terminal region of a manipulative guide link to provide for a strutlike link extension, one end of the strutlike link being mounted on the supplementary pivot and the opposite 30 terminal of the guide link being pivotally attached to said face to permit of swinging the jointed end of the guide link between extreme shift positions respectively lying alongside said face forwardly and rearwardly of such pivotal attachment, the strutlike link extension being disposed to thrust against the board face to retain the erected rear leg structure against collapse when the toggle linkage assumes a rearward position and which extension spacedly holds the 40 jointed end of the guide link away from said face, a cooperative auxiliary toggle linkage comprising a pair of jointed links pivotally suspended between the foot pivot of the erected front leg and the retained rear leg structure, and stop means 45 interposed between the front leg and one such suspended link serving to prevent toggle alignment with the other suspended link, the toggle joint of such auxiliary linkage being arranged to automatically recede from said face when the guide link is swung away from its extreme rearward position.

2. In a collapsible table or the like adapted to unfold into erected position, a top board, a front leg having one end pivoted to the board, a foot 55 pivot on the opposite end region of the front leg, a rear leg structure also pivoted to the board, supplementary pivot means located between the ends of said structure, manipulative link means extending between the supplementary pivot and the board serving to guide the rear leg structure from collapsed into a retained erected position, a cooperative toggle linkage comprising a pair of jointed links pivotally suspended between the foot pivot of the erected front leg and the retained rear leg, and stop means for one such suspended link serving to prevent toggle alignment with the other suspended link, the interposed toggle joint thereof being arranged to automatically recede from said face and being operative 60 by the manipulative link means to initiate a collapsing movement on part of the several erected legs.

3. In a collapsible table or the like adapted to unfold into erected position, a top board, a front 70

- leg having one end region pivoted to the board, a foot pivot on the opposite end region of the front leg, a structure comprising a pair of rear legs also pivoted to the board, a supplementary pivot 5 located between the respective ends of each rear leg, manipulative link means extending between the supplementary pivots and the board serving to guide said rear legs between collapsed and erected positions, and a toggle linkage disposed 10 between the foot pivot and said pair of rear legs whereby the front leg is actuated in unison with the guided rear legs, said linkage comprising a pair of jointed link components of different lengths of which the free end of the shorter link 15 component is mounted on the foot pivot and the free end of the longer link component is given a unitary ball shape of which the bifurcated terminal regions are respectively attached to a different rear leg and arranged to constitute the 20 aforesaid supplementary pivots thereof and the medial nose region of which bail pivotally engages the other end of the shorter link component to constitute the toggle joint of such linkage.
4. In a collapsible table or the like adapted to 25 unfold into erected position, the combination of a top board, a front leg having one end region pivoted to one board face, a foot pivot carried by the opposite end region of the front leg, a rear leg structure also pivoted to said board face,
- supplementary pivot means located on said structure between the ends thereof, a primary toggle linkage including a strutlike link having one end pivotally jointed to one terminal region of a manipulative guide link, the other end of the 5 strutlike link being mounted on the supplementary pivot and the opposed terminal of the guide link being pivotally attached to said face to permit of swinging the jointed end of the guide link through its aligned dead center into a buckled 10 toggle position lying rearwardly of such pivotal guide link attachment and wherein said toggle linkage serves to retain the erected rear leg structure against collapse, a cooperative auxiliary toggle linkage comprising a pair of jointed 15 links of different lengths pivotally suspended between the foot pivot of the erected front leg and the retained rear leg structure, and stop means operatively interposed between the shorter link and said front leg serving to prevent toggle alignment with the longer link, the stop means being disposed to automatically recede from said face when the guide link is swung away from its buckled position and the respective linkages being so arranged that the primary linkage when 20 manipulated cannot become stalled because of link alignment on part of the auxiliary linkage.
- 25
